UNITED STATES PATENT OFFICE

HERMAN ISKIN, OF PHILADELPHIA, PENNSYLVANIA

PLAY SUIT

Application filed July 10, 1928. Serial No. 291,679.

This invention relates to clothing, and its chief object is to provide a "cow-boy" play-suit in which both the trousers and the chaps, usually separately included in such an outfit, will be constituted by a single unitary garment, which will present the appearance, nevertheless, of a cowboy play-suit made up of separate chaps over trousers.

Another object of the invention is to provide a play suit which, though to all appearances a pair of chaps (which of course have no seat), will nevertheless have a full-back drop seat adapted to be held up in the back by a member forming part of the front of the chaps, but which will engage with the drop seat and fasten thereover only in the back; thereby permitting, among other advantages, a full back-opening by a simple, quick manipulation.

A further object of the invention is to provide a cowboy-suit of this nature which will have but one, simple, unitary device for holding up both the chaps and the trousers part of the garment, and the drop-seat part as well.

A particular object of the invention is to provide a chaps and trousers outfit which can be made with no more stitching and requiring but little more cloth than ordinary overall trousers, to thereby lower considerably the price of play suits.

My improved garment is shown in the accompanying drawings, and will be described in detail hereinafter, but is limited in its embodiment only by the scope of the subjoined claim.

In these drawings:

Fig. 1 is a front view of the garment, unfastened;

Fig. 2 is a rear view thereof;

Fig. 3 is a rear view, showing the drop seat down and the suspending or holding means unfastened, and

Fig. 4 is a detail of the suspending or holding means with the seat up.

Referring now more in detail to the invention by means of the drawings, the garment comprises a strip or piece 1 made to cover the front of the legs, extending part way into the crotch, and all the way up to the waist in the front only, and made of any suitable wear-resisting material which resembles leather, animal skins, or the like, such as processed plush. Flaps 1' are formed by attaching a stiff strip of imitation leather, oil cloth or the like, to further enhance the chaps-like appearance of the garment by providing a semblance of the leg-guards of regular chaps.

The entire back of the legs and the seat is preferably formed of a single large piece of khaki cloth, or the like, 2 extending from waist to the cuff of the garment, and forming a seat integral with the back of the legs.

The garment, though unitary in its nature, and having a complete, full back thus, nevertheless presents the appearance of a regular service outfit consisting of separate leather or fur chaps worn in the regular manner over cloth trousers.

The back of the garment is made separate from the front, at the sides, down to the points 10, as shown, and this separate portion is formed into a full back drop seat 11.

The presence of this formation, however, is discernible only by the gaps in the sides where the back joins the front, and these gaps may be kept closed by suitable snap-fasteners or the like, 14. The chaps effect is not impaired or interfered with in any way by this construction and arrangement of the drop seat, and the drop seat can be manipulated easily and quickly to give a full rear opening.

To hold up the garment, and to complete the similitude of chaps over trousers, a strap of leather or the like, 5, is formed in the front of the waist of the garment and is attached to the garment only at that point, and in addition to holding up the garment, forms a reinforcement for the front upper edge of the garment.

This member is formed at one side into a tongue-extension 6, of a considerable length, and having a buckle 7 or the like fastened on its end. This extension is made long enough to reach around at least to the middle of the back. The other side of the strip 5 is extended in the opposite direction a length 8 sufficient to at least reach the part 6, and this extension 8 has suitable buckle holes 9 or the like therein to engage with the buckle on the other extension.

The drop-seat 11, at its upper edge, in the waist, has belt-loops or keepers 13 formed thereon, and the drop-seat is held up by passing the strap 6 through its loops 13, passing the strap 8 through its loops 13, and buckling the two extensions 6 and 8 of the front-attached belt together in the back over the drop seat, to thereby not only hold up the drop-seat against the waist,—and in such a manner as to permit of a full rear opening,—but at the same time to hold up the entire garment suspended from the waist and to maintain both front and rear smooth and neat.

This device can be readily and quickly buckled and unbuckled, and the seat will then drop down fully, and thus, though the garment is to all appearances and effects a pair of full size regular chaps over trousers, it is notwithstanding particularly well adapted to be readily manipulated by children in a hurry and is withal a cheap and simple but unitary and durable single-garment play suit.

I claim:

A cowboy playgarment comprising a front piece of material of the kind used for chaps and rear piece of material of the kind used for trousers, pieces of material extending from the outside of both legs and forming flaps, a belt around the waist portion of said garment, wider in front and permanently fastened to said front piece, belt-loops on said rear piece adapted to receive said belt and a drop seat in said rear piece adapted to be supported by said belt and belt loops and fastened to said front portion by snap fasteners along the sides.

40 In testimony whereof I affix my signature.
HERMAN ISKIN.
